(57) **CLAIM**

The ornamental design for an LED light tube, as shown and described.

DESCRIPTION

FIG. 1 is a perspective view of an LED light tube showing my new design;

FIG. 2 is an enlarged, front elevational view of the LED light tube of FIG. 1 with a middle portion removed for ease of illustration;

FIG. 3 is an enlarged, rear elevational view of the LED light tube of FIG. 1 with the middle portion removed for ease of illustration;

FIG. 4 is an enlarged, left side elevational view of the LED light tube of FIG. 1 with the middle portion removed for ease of illustration;

FIG. 5 is an enlarged, right side elevational view of the LED light tube of FIG. 1 with the middle portion removed for ease of illustration;

FIG. 6 is an enlarged, top plan view of the LED light tube of FIG. 1 with the middle portion removed for ease of illustration;

FIG. 7 is an enlarged, bottom plan view of the LED light tube of FIG. 1 with the middle portion removed for ease of illustration; and,

FIG. 8 is a cross-sectional view taken along line 8-8 of the LED light tube of FIG. 2.

The shade lines show contour and not surface ornamentation. The broken lines are environmental and form no part of the claimed design.
